CHILD'S SLEEPING BAG

Donald J. Dale, 715 W. Minnehaha Parkway,
Minneapolis, Minn. 55419

Filed Apr. 4, 1968, Ser. No. 11,304

Term of patent 14 years

Int. Cl. D6—02; D21—99

U.S. Cl. D92—2

Fig. 1

I claim:

The ornamental design for a child's sleeping bag, as shown and described.
